UNITED STATES PATENT OFFICE.

JOHN P. EUSTIS, OF NEWTON, MASSACHUSETTS.

DESIGN FOR A MIRROR OR PICTURE FRAME.

No. 39,639.

Specification for Design.

Patented Oct. 27, 1908.

Application filed July 6, 1908. Serial No. 442,263. Term of patent 14 years.

To all whom it may concern:

Be it known that I, JOHN P. EUSTIS, a citizen of the United States of America, residing at Newton, in the county of Middlesex and State of Massachusetts, have invented a new, original, and ornamental Design for Mirror or Picture Frames, of which the following is a specification, reference being had to the accompanying drawings, forming part thereof, and in which—

Figure 1 is a plan, and Fig. 2 is a side elevation of the frame.

The design comprises an oval face *a*, an oval side surface *b* at right angles to the face, an oval outwardly curved rim *c*, and a beading *d* at the juncture of the oval face and the oval side surface.

I claim—

The ornamental design for a mirror or picture frame, substantially as shown.

JOHN P. EUSTIS.
